UNITED STATES PATENT OFFICE.

HARRY F. LA RUE AND WILLIAM ZIERLEIN, OF FAIRFIELD, IOWA.

DESIGN FOR A SMOKER'S STAND.

Application filed November 18, 1926. Serial No. 19,772. Term of patent 14 years.

To all whom it may concern:

Be it known that we, HARRY F. LA RUE and WILLIAM ZIERLEIN, citizens of the United States, residing at Fairfield, in the county of Jefferson and State of Iowa, have invented a new, original, and ornamental Design for a Smoker's Stand, of which the following is a specification, reference being had therein to the accompanying drawings.

What we claim is:

The ornamental design for a smoker's stand as shown.

In testimony whereof we hereunto affix our signatures.

HARRY F. LA RUE.
WILLIAM ZIERLEIN.
